CLAIM

The ornamental design for a wearable electronic device, as shown and described.

DESCRIPTION

FIG. 1 is a perspective view showing the front and right side of a wearable electronic device showing our new design; FIG. 2 is a top plan view thereof, the bottom plan view being a mirror image thereof;

FIG. 3 is a right side view thereof;

FIG. 4 is a left side view thereof;

FIG. 5 is a sectional view taken along line 5-5 of FIG. 3; and, FIG. 6 is a side sectional view taken along line 6-6 of FIG. 1.

The broken lines shown in FIGS. 1, 3, and 5 illustrate portions of the wearable electronic device and form no part of the claimed design.
